Robert H. Beaumont

FIG. 1.

INVENTOR

Robert H. Beaumont
BY
Augustus B. Strongton
ATTORNEY

UNITED STATES PATENT OFFICE.

ROBERT H. BEAUMONT, OF RADNOR, PENNSYLVANIA, ASSIGNOR TO R. H. BEAUMONT COMPANY, OF PHILADELPHIA, PENNSYLVANIA, A CORPORATION OF PENNSYLVANIA.

SKIP-HOIST STRUCTURE.

Application filed May 4, 1928. Serial No. 275,057.

In skip hoists there is a cable operating from the top and to it is attached a bucket bail guided by upright and inclined tracks. Heretofore, so far as I know, the adjacent ends of the upright and inclined tracks have been connected by curved tracks of long radius. The maximum rope pull and track reaction occurred at these curved tracks and a construction including these curved tracks was difficult to figure and to lay out and to construct and the curved tracks were difficult to hold in place.

The principal object of the present invention is to lessen the track reactions and rope pulls and to provide a construction simpler to detail and easier to hold.

According to the present invention the inclined and upright tracks are connected by tangent tracks, that is, straight short cut tracks which operate to lessen the maximum loads to which reference has been made and which occur where the ends of the upright and inclined tracks are connected by means of curved tracks of long radius according to practice heretofore followed.

The invention also comprises the improvements to be presently described and finally claimed.

In the following description reference will be made to the accompanying drawing forming part hereof and in which

Figure 1 is an elevational view illustrating the lower inclined tracks connected with the vertical tracks in accordance with the present invention and by means of tangent tracks, and

Fig. 2 is a similar view illustrating the application of the present invention to the upper part of a skip hoist run.

In the drawing 1 generally indicates the vertical tracks, 2 generally indicates the inclined tracks at the bottom of the structure, and 3 the inclined tracks at the top of the structure. 4 is a cable or rope operating from the top of the structure and it is shown as guided by sheaves 5 carried by the framework or structure 6 of the tower. The bail 7 of the bucket 8, or more accurately, the guide wheel 9 of the bail runs between the tracks and is

guided by them, and to the bail is attached the cable 4. 10 generally indicates the tangent tracks or straight short cut tracks by which the vertical tracks 1 are connected with the inclined tracks 2 and 3.

In use the tangent tracks 10 approach vertical direction at once and thereby reduce the track thrust to a minimum which lessens the rope pull and maximum effort of the driving machinery. Another way of explaining the operation of the described tangent tracks is to compare their operation and results with the operation and results of curved tracks such as have been heretofore employed. When any tracks are parallel with the rope pull the best conditions obtain, and if the tracks were at right angles to the rope pull the worst conditions would obtain. In the second case the angle corresponding to the angle α , Fig. 1, is 180° , and in the first case it is 90° , consequently the smaller the angle α the better are the conditions for limiting the maximum rope pull and track thrust. Referring to Fig. 1, b represents the rope pull, c the track thrust, and d the bail pull, and in that particular case the angle α is 70° and the angle e between c and the horizontal is $19^\circ 11'$. Assuming that the dead weight of the bucket equals 100% the rope pull b equals 80%, and the track thrust c equals 54%. All other things remaining the same, if the inclined tracks 2 and the upright or vertical tracks 1 were connected by a curved track of long radius, the angle corresponding with α would equal 60° , the angle corresponding with e would equal 32° , the rope pull would equal 90%, and the track thrust would equal 60%. The bail pull in each case is 80%.

It may be remarked that the sharp bends where the tangent tracks join the inclined and vertical tracks are in the direction of stress on the wheel 9 and therefore are unobjectionable. In connection with the comparison between the tangent and curved connecting tracks, it may be said that the conditions recited refer more particularly to the entrance portion of the curved tracks and of course as the latter approach the vertical the pull and thrust

diminish but the maximum pull and thrust with the curved tracks exceed the maximum pull and thrust with the tangent tracks, and it is the maximum pull and thrust that have to be taken care of.

It will be obvious to those skilled in the art to which the invention relates that modifications may be made in details of construction and arrangement and in matters of mere form without departing from the spirit of the invention which is not limited to such matters or

otherwise than the prior art and the appended claim may require.

I claim:

In a skip hoist having a cable operating from the top and the bucket bail attached to the cable and including relatively inclined tracks for guiding the bail, means for connecting the inclined tracks which comprise tangent tracks, substantially as described.

ROBERT H. BEAUMONT.
